PROPELLING MAGAZINE PENCIL

Vojtech Votruba, Ceske Budejovice, Czechoslovakia, assignor to Koh-I-Noor Pencil Factory L. & C. Hardtmuth, Ceske Budejovice, Czechoslovakia, a company of Czechoslovakia

Application October 25, 1946, Serial No. 705,722.
In Czechoslovakia October 26, 1945.

6 Claims. (Cl. 120—14.3)

1

This invention relates to a pencil of the type in which four different coloured leads are contained in a casing within the pencil housing and are adapted to be selectively brought to the writing position.

According to this invention, a magazine pencil includes a guide sleeve which is closed at its lower end by an abutment disc formed with a bevelled projection, and four lead barrels symmetrically disposed within said sleeve when the pencil parts are in a position of rest.

In the accompanying drawing:

Fig. 1 is a longitudinal section of a magazine pencil according to the invention;

Figs. 2—4 are sections on the lines II—II, 15 III—III and IV—IV, respectively, of Fig. 1;

Fig. 5 is a perspective view of the lead selecting means of the pencil; and

Fig. 6 is a perspective view of the casing holding the lead barrels and forming part of the pencil shown in Fig. 1.

Referring to Fig. 1, a magazine pencil comprises a housing 1 containing a casing 2 in which are fitted four barrels 4, each adapted to receive a coloured lead. The magazine casing 3 fits into a guide sleeve 5, which is inserted in the pencil housing 1, the upper end of said sleeve being rigidly fixed in the housing 1 by means of a threaded ring 6.

The four lead barrels 4 enclosed in the magazine casing 3 are each closed at the upper end by a plug 11, each plug being connected by means of a spring 12 to a press knob or button 13. By this means, the barrels 4 can be deflected at their lower ends as hereinafter described and this is utilized in the changing and selection of the leads. The casing 3 has four parallel inwardly directed indentations 14 extending longitudinally of and so formed on said casing 3 that there is a lead barrel 4 between each pair of indentations (see Fig. 3). Two oppositely disposed projections 15 on the inner wall of the guide sleeve 5 (Figs. 2 and 6) are adapted to engage the indentations 14. The sleeve 5 is also provided with four longitudinal cuts 22 arranged in pairs on opposite sides of the sleeve, each pair arranged on opposite sides of one of the projections 15 (see Fig. 6). The slots 22 and projections 15 together exert a kind of spring action when the latter have engaged the indentations 14, forming a safety device acting to a certain extent against any rotation of the press button 13. When the two projections 15 on the sleeve 5 exactly engage two indentations 14 in the casing 3, the pencil is in the writing position.

2

The press button 13 is fixed on the magazine casing 3 and is provided around its periphery with four coloured marks which indicate the colors of the respective leads in the barrels. The lower end of the button 13 is flanged at 17, said flange being adapted to abut against an internal flange on the top 18 of the pencil housing 1, whereby the casing 3 cannot be forced out of the housing 1.

The lead selecting mechanism of the new magazine pencil described above consists of the annular closure disc 8 which is arranged within the sleeve 5 at the lower end thereof firmly secured to the sleeve and provided with an upwardly extending projection 8'. This projection 8' forms, as clearly shown in Fig. 1, an inwardly inclined abutment at its upper end against which the free end of the selected lead barrel 4 abuts and is guided into lead changing position as will be described farther along in detail.

In order to avoid unwanted falling out of the leads from the lead barrels 4 and to return the lead barrels together with the button 13 from lead changing into inoperative position, there is provided within the sleeve 5 a disc-shaped bottom member 7 clearly shown in Figure 5. This disc-shaped bottom member 7 is provided with an annular extension 7' fitting into the opening in the annular closure disc 8 so as to support the bottom member 7 freely slidably in axial direction of the pencil. The bottom member 7 as well as the annular extension 7' are provided with a groove 7" corresponding to the upwardly extending projection 8' of the annular closure disc 8 so as to enable free sliding of the bottom member 7 between its lead changing position shown in Figure 1 and its inoperative position, not shown in the drawing, in which the upper face of the bottom member 7 is located in the plane of the inclined abutment at the upper end of the projection 8'.

The annular extension 7' of the bottom member 7 is firmly secured to the extension sleeve 9 of the clamping tube 10 for the selected lead, as shown in Figure 1. This clamping tube 10 is freely slidable in the metal point 21 which in turn is rigidly secured to the pencil housing 1. Both the bottom member 7 and the annular extension 7' are provided with the hole 20 through which the lead from an inwardly deflected lead barrel is able to drop into the extension sleeve 9 and the clamping tube 10.

Spring 19 arranged as shown in Figure 1 abuts against an annular disc secured to the extension sleeve 9 and permanently tends to move this

sleeve together with the clamping tube 10 and the annular extension 7' and bottom member 7 upward into inoperative position in which the clamping tube 10 is located in a corresponding recess in point 21 and the upper face of the bottom member 7 is located in the plane of the inclined abutment at the upper end of the projection 8'.

It should be stressed, however, that, as clearly shown in Figure 1, the recess at the bottom of point 21 is shaped so that the clamping member 10 is able to enter the recess only if it is slightly compressed. Consequently, if a lead is located in the clamping member 10 held by the same, spring 19 is unable to slide the extension 9 together with the clamping member 10 and the bottom member 7 into inoperative position in which all four lead barrels 4 are in parallel inoperative position.

The new magazine pencil described above operates as follows:

If there is no lead in the clamping member 10, spring 19 moves the same together with extension sleeve 9 and bottom member 7 into inoperative position not shown in the drawing, in which position, as set forth above, the upper face of the bottom member 7 is located in the plane of the inclined abutment at the upper end of the projection 8'. In such inoperative position, all four lead barrels 4 are held by the springs 12 in parallel outwardly disposed position closed at their lower ends by the upper face of the bottom member 7 and the abutment at the upper end of extension 8'.

If it is desired to select a certain color, the button 13 is turned until the selected lead barrel 4 is located above the extension 8'. Next, the button 13 is pressed in downward direction. This will result in sliding of the selected lead barrel along the inclined abutment of projection 8' into the lead changing position shown in Figure 1, cooperating with the hole 20 in the bottom member 7; simultaneously, the other lead barrels will press against this bottom member, moving the same together with the clamping tube 10 into the lead changing position shown in Figure 1.

In this position, the selected lead drops into the clamping member 10. When it reaches its proper writing position, the button 13 is released and spring 19 is free to slide the clamping member 10 upward until member 10 abuts at its upper end against the point 21, firmly holding the selected lead.

In this writing position, as explained above, the clamping member as well as the bottom member 7 have not yet reached their inoperative position so that the selected lead barrel 4 will still be deflected inwardly cooperating with the opening 20 in the bottom member 7 and preventing unintentional turning of button 13.

If it is desired to change to another color, the pencil is turned upside down and the button 13 depressed, permitting the lead from the clamping member 10 to drop back into the proper lead barrel. Then, the button 13 is released and another desired lead selected as described above.

What I claim is:

1. A magazine pencil comprising in combination a casing; a channel at the forward end of said casing; an internal chamber provided lengthwise in said casing; a plurality of lead holders disposed symmetrically within said chamber; a closure disc disposed in said chamber at its forward end; an opening formed centrally in said closure disc providing a communication between said chamber and said channel; an

abutment arranged on said closure disc, the said abutment having a face sloping toward the said central opening; actuating means disposed at the rear end of said casing and being revolvable in relation thereto and being movable inward; and a connection between said actuating means and the rear end of each of said lead holders for bringing a selected lead holder into contact with said abutment and then urging the said lead holders inward and thus moving the selected holder along said abutment to bring its inner end in alignment with said opening whereby a lead may be dropped from said holder through said opening and channel.

2. A magazine pencil comprising in combination a casing; a channel at the forward end of said casing; an internal chamber provided lengthwise in said casing; a plurality of lead holders disposed symmetrically within said chamber; a closure disc disposed in said chamber at its forward end; an opening formed centrally in said closure disc providing a communication between said chamber and said channel; an abutment arranged on said closure disc, the said abutment having a face sloping toward the said central opening; actuating means disposed at the rear end of said casing and being revolvable in relation thereto and being movable inward; and individual spring members connecting the rear end of each of said lead holders with said actuating means for bringing a selected lead holder into contact with said abutment and then urging the said lead holders inward and thus moving the selected holder along said abutment to bring its inner end in alignment with said opening whereby a lead may be dropped from said holder through said opening and channel.

3. A magazine pencil constructed in accordance with claim 1 including clamping means disposed in said channel; spring means for urging said clamping means inside said channel; and a thrust member being connected at one end to said actuating means and acting with its other end on said clamping means so as to force the same outside of said channel, thus releasing the lead disposed in said channel.

4. A magazine pencil comprising in combination a casing; a channel at the forward end of said casing; an internal chamber provided lengthwise in said casing; a plurality of lead holders disposed symmetrically within said chamber; a closure disc disposed in said chamber at its forward end; an opening formed centrally in said closure disc providing a communication between said chamber and said channel; an abutment arranged on said closure disc, the said abutment having a face sloping toward the said central opening; actuating means disposed at the rear end of said casing and being revolvable in relation thereto and being movable inward; a guide sleeve disposed in said casing and surrounding said lead holders, the said guide sleeve being connected to said actuating means; and a connection between said actuating means and the rear end of each of said lead holders for bringing a selected lead holder into contact with said abutment and then urging the said lead holders inward and thus moving the selected holder along said abutment to bring its inner end in alignment with said opening whereby a lead may be dropped from said holder through said opening and channel.

5. A magazine pencil comprising in combination a casing; a channel at the forward end of said casing; an internal chamber provided lengthwise in said casing; a plurality of lead holders

disposed symmetrically within said chamber; a closure disc disposed on said chamber at its forward end; an opening formed centrally in said closure disc providing a communication between said chamber and said channel; an abutment arranged on said closure disc, the said abutment having a face sloping toward the said central opening; actuating means disposed at the rear end of said casing and being revolvable in relation thereto and being movable inward; a guide sleeve disposed in said casing and surrounding said lead holders, the said guide sleeve being connected to said actuating means; clamping means disposed in said channel; spring means for urging said clamping means inside said channel; an operative connection between said guide sleeve and said clamping means whereby said clamping means are forced outside said channel upon inward movement of said actuating means; and a resilient connection between said actuating means and the rear end of each of said lead holders for bringing a selected lead holder into contact with said abutment and then urging the said lead hold-

ers inward and thus moving the selected holder along said abutment to bring its inner end in alignment with said opening whereby a lead may be dropped from said holder through said opening and channel.

5 6. A magazine pencil constructed in accordance with claim 5 and including an inner support member for the inner ends of said lead holders, the said support member being normally spaced inwardly from said closure disc and being movable into contact therewith; and a slot provided on said support member for permitting said abutment to pass therethrough.
